FLASH ARRESTER FOR DRAFT INTAKE OF
FURNACE FIREBOXES

William O. Moran, Tulsa, Okla.

Original application October 14, 1948, Serial No.
54,451. Divided and this application July 8,
1952, Serial No. 297,617

3 Claims. (Cl. 126—85)

1

This invention is directed to improvements in a flash arrester for the air intake of a furnace firebox and is a divisional application of my co-pending application Serial No. 54,451, filed October 14, 1948.

While the flash arrester, according to my invention, is not limited in this particular use, it is extremely well adapted for use on heaters or furnaces used in heating of meter houses and other like buildings associated with oil refineries, oil production fields, tank farms, and on pipe lines. Such heaters or furnaces used in connection with heating pipe lines and meter houses are used where there is a distinct possibility of leakage of petroleum, particularly the more volatile fractions of petroleum, and the contamination of the atmosphere with vapors of such volatilized petroleum vapors as well as natural gases themselves. At times, the concentration of such vaporized and gaseous products in the atmosphere forms a mixture which is capable of ignition, even explosion, if subject to a flame or spark. Thus, it becomes imperative that the flame within the burner chamber or firebox of the furnace be held within the firebox and not allowed to communicate with the atmosphere adjacent the firebox at the draft intake thereof. Thus, I have provided a flash arrester which will prevent flame or spark from passing out of the firebox and into the surrounding atmosphere which might ignite a possible combustible atmosphere outside the firebox. Further, since the air intake of the heater or furnace is exposed to wind blowing from all directions and at different forces it is essential that the air intake to the furnace be baffled so that the full force of the wind does not directly impinge upon the flame in the firebox which might result in the extinguishment of the flame.

It is thus the primary object of my invention to provide an attachment for the air intake of a furnace firebox which will permit the passage of air therethrough to support combustion but will prevent the passage of flame back through the arrester to the outside atmosphere.

Another object of my invention is to provide a flash arrester with a hood and baffle arrangement which will prevent entrance of air in force and quantity to extinguish the flame in the firebox with which the flash arrester is used.

2

A further object of my invention is to provide a flash arrester which may be easily attached to the air intake of a furnace or boiler which incorporates a plurality of spaced fine-mesh screens to prevent flame from passing therethrough and includes baffles and hood for directing the air supply in such quantity and force that it will not extinguish the flame in the firebox of the heater or boiler to which the flash arrester is attached.

A still further object of the invention is to provide a flash arrester consisting of an elongated housing adapted for attachment at one end to the intake opening of a firebox on a heater or furnace while the other end is provided with a hood and baffle arrangement which permits intake air to enter through a circuitous path and the elongated housing has positioned adjacent the hood attached end and within the confines of the housing, a rigid shell with means for connecting the shell to the surrounding elongated housing so as to provide a tight closure therebetween with the rigid shell carrying transversely disposed and spaced apart fine-mesh screens which permit passage of air therethrough but prevent the passage of a flame.

Still further objects and the entire scope of applicability of the present invention will become apparent from the detailed description given hereinafter; it should be understood, however, that the detailed description and specific examples are given by way of illustration only and, while indicating preferred embodiments of the invention, are not given by way of limitation, since various changes and modifications within the spirit and scope of the invention will become apparent to those skilled in the art from this detailed description.

For a more complete understanding of the invention reference may be had to the drawings in which:

Figure 1 is a cross section view of a meter house having a heater installed with a heater provided with a flash arrester;

Figure 2 is an elevational end view of the flash arrester as viewed from within the firebox end of the flash arrester;

Figure 3 is a cross sectional view as viewed along section lines 3—3 of Figure 2;

Figure 4 is a bottom view of the flash arrester as seen from section lines 4—4 in Figure 2;

Figure 5 is a cross sectional side elevation of a modified form of flash arrester having a conical shaped baffle and a conical hood;

Figure 6 is an end view of the flash arrester shown in Figure 5 as viewed from the right-hand side thereof; and

Figure 7 is an end view showing the conical baffle and the flash arrester as viewed along section line 7—7 in Figure 5.

Throughout the description and the various figures of the drawings like reference numerals refer to similar parts.

In Figure 1 there is shown a meter house generally indicated at 10 having a safety heater 11 projecting thru an end wall 10' thereof and disposed in a horizontal position with its intake covered by a flash arrester 12 according to my invention and with an exhaust stack disposed exterior of the meter house 10 as indicated at 13. The exhaust stack is provided with draft equalizing cap 14 on the top end thereof.

The flash arrester shown in Figures 2, 3 and 4 is the flash arrester 12 as shown mounted on the heater 11 in Figure 1. The modified form of flash arrester shown in Figures 5, 6 and 7 can equally as well be mounted on the air intake end of the heater 11 instead of the flash arrester 12.

The flash arrester 12, as best shown in Figure 3, includes an elongated housing 15 which may be circular in shape depending upon the type of heater or furnace with which it is used, and this elongated housing 15 is adapted to fit over the air intake end of the firebox of the heater or furnace. The elongated housing 15 has its rear end provided with a transversely extending flange 16, see Fig. 3, which is apertured throughout its greater central portion 16' to provide for entrance of air into the elongated housing 15. This flange 16 also provides for mounting of other parts of the flash arrester and in order to mount these parts it has a plurality of circumferentially spaced apertures 16" for receiving the through bolts 17. Mounted within the rear or air intake end of housing 15 is a first fine-mesh screen 18 which extends transversely across the cross section of the housing 15 and at its peripheral rear face abuts against the inside of flange 16. This screen 18 is provided with a plurality of spaced apertures 18' about its peripheral face which are received over the through bolts 17. Mounted against the other peripheral face of screen 18 and having the bolts 17 passing through suitably spaced apertures therein is an asbestos washer or ring 19 which has mounted thereagainst a second fine-mesh screen 20 in spaced relation to the first fine-mesh screen 18 and this second screen 20 is provided with a plurality of spaced apertures 20' about its peripheral portion so as to be received over and secured by the through bolts 17. A rigid shell 21 of elongated cylindrical shape is received over the through bolts 17 with its rear end riding against the second fine-mesh screen 20.

A third fine-mesh screen 22 having a plurality of spaced apertures 22' so as to be received over the through bolt 17 is mounted against the inner end of the shell 21 and is secured thereagainst by means of a circular ring or washer 23 which is also provided with a plurality of circumferentially spaced apertures 23' so as to be received over the through bolts 17. The whole assembly of rigid shell and fine-mesh screens and washers are held together by the through bolts 17 having take-up nuts 17' on the inner ends thereof.

On the rear end of the elongated housing 15 or the other end from the furnace end mounting is mounted a hood generally indicated at 24 which has as its lower portion a semi-cylindrical skirt 25 fabricated from sheet metal as is the other housing 15 and shell 21 portions of the whole flash arrester. This semi-cylindrical skirt 25 is formed with a transversely extending flange 26 along its forward end and is provided with up-standing side portions 26' so as to provide for an air passage in alignment with the aperture 16' in the central portion of the flanged end 16 of elongated housing 15. The transversely extending end 26 and its portions 26' on either side are provided with apertures 27 in alignment with the through bolts thereadjacent as indicated at 17 and 17' in Figure 3. Over the lower through bolt 17, as shown in Figure 3, is secured a baffle 28 having a flange 29 on the forward end thereof which extends downward at an acute angle and is apertured for mounting over the lower through bolts 17 as shown. This baffle 28 extends downwardly and rearwardly at an incline within the semi-cylindrical skirt 25 of hood 24 and at its rear end 28' is in spaced relation to the adjacent portion of skirt 25, as best shown in the bottom view in Figure 4.

In Figure 4 it will be noted that the baffle 28 is semicircular and the flange 29 thereof extends across as the diameter and is supported by the adjacent through bolts 17. It will be noted that an arcuate moon-like shaped aperture is formed between the rear edge 28' of the baffle 28 and the skirt portion 25 of housing 24 which aperture provides for the passage of air therethrough from the lower open end 25' of the hood 24, up into the skirted hood 25 and on into the opening 16' of elongated member 15.

Still referring to Figure 3 it will be noted that the upper portion of hood 24 is provided with an inclined roof section 29 attached to skirt portion 25. Roof portion 29 is formed with a horizontally extending semi-circular lip portion 29' at the forward end thereof which projects a short distance over the rear end of the elongated housing 15 and forms an air passageway as indicated at 30 therebetween the elongated housing 15 and the lip 29'. The roof portion 29 is supported by bracket members 31 which have angularly bent end portions 31' and 31'', 31' of which is apertured and received over one of the through bolts 17, while bent portion 31'' is apertured and has a bolt 32 passing therethrough securing it to the roof 29 of hood 24. Thus, there is provided by the hood 24 an air passageway at 30 at the upper portion thereof which leads to the end opening 16' in housing 15 and one at the opposite portion at end 25' adjacent baffle 28 at the lower end of the hood 24. No direct drafts of air can blow into the flash arrester but the draft air must pass through circuitous passageways for entrance to the flame arrester. This construction provides for an even flow of draft air into the flame arrester and particularly through the spaced fine-mesh screens within the elongated housing 15. Draft air passes through these fine-mesh screens into the firebox to which this flame arrester is attached, however, flame from within the firebox will not pass back through these spaced fine-mesh screens and into the hood and out into the surrounding atmosphere. Thus, if this flame arrester is used on a heater or furnace within an atmosphere of combustible vapors, a safety feature is provided in that the flame in the furnace housing will not feed back through the flame

arrester since the spaced fine-mesh screens provide a barrier. While in some extreme cases a small portion of flame might pass through the third fine-mesh screen 22 adjacent the firebox, however, a spacing between the third screen 22 and the second screen 20 is such that the flame will not extend therebetween nor be able to feed back through the spaced first and second screens 18 and 20 as best shown in Figure 3.

The modified form of flame-arrester as shown in Figures 5, 6 and 7 will now be described. Referring to Figure 5, there is shown an elongated housing 15' which may be circular in shape dependent upon the furnace with which it is being used. Housing 15' is provided with inturned flanges 16' at its rear end which are apertured and received through bolts 17 as in the flame arrester shown in Figure 3. In the form of flame arrester shown in Figure 5 the first fine-mesh screen 18' is mounted adjacent the rear face of flange 16' instead of within the flange as shown in Figure 3 for the first described flame arrester. The second fine-mesh screen 20' is mounted adjacent the opposite face of flange 16' and is held tightly thereagainst by means of the rigid cylindrical shell 21' and the through bolts 11. The third fine mesh screen 22' is mounted over the end of the rigid shell 21' and adjacent thereto and secured thereagainst by means of the circular ring or washer 23' by means of the through bolts 17 and the take-up nuts 17'.

Instead of the hood and baffle arrangement shown in Figures 2, 3 and 4, I provide for a conical shaped hood generally indicated at 40 which has an open end 41 and a lip portion 42 extending in spaced relationship about the rear end of the elongated housing 15' and thus there is formed an air receiving passageway 43 about the end 15', as best shown in Figure 6. This conical shaped hood 40 is supported in spaced relationship on the rear end of housing 15' by means of brackets 44 which have their forward ends bent at right angles and apertured and received over through bolts 17 as indicated at 45 in Figure 5 while their rear ends are formed with an angle 46 and apertured to receive the through bolts 47 which secure them to and support the conical shaped hood 40. Four of these brackets 44 are shown equally spaced for supporting the hood as best shown in Figure 7.

In Figure 5 there is shown a conical shaped apertured baffle 48 provided with a plurality of spaced apertures 49 in the wall thereof while the open end of the conical shaped baffle is provided with a transverse outwardly extending flange 50 which is provided with a plurality of spaced apertures about its circumference for mounting over the through bolts 17 as best shown in Figure 5. It will be noted that the hood 40 is mounted in spaced relationship about the conical aperture baffle 48 and there is provided a passageway for air to be received between the hood 40 and the baffle 48 and passed through the apertures 49 of the baffle 48 on into the elongated housing 15 through the flame arresting screens 18', 20' and 22'. As in the flame arrester described in Figure 3, air is permitted to pass into the flame arrester but the flame from within the firebox to which the flame arrester is attached is prevented from passing back through the flame arrester by means of the transversely extending spaced fine-mesh screen therein.

Since it is obvious that certain further changes can be made in the foregoing constructions without departing from the spirit and scope it is in-

tended that all matter shown in the accompanying drawings or described hereinbefore shall be interpreted as illustrative and not in a limiting sense.

5 I claim as my invention:

1. A flame arrester for the air intake of a furnace firebox comprising, in combination, an elongated housing having one end thereof adapted to be connected with the air intake of a furnace firebox, a rigid shell disposed within said housing adjacent the other end thereof, means connecting said shell to said surrounding elongated housing providing a tight closure therebetween, a plurality of spaced apart fine-mesh screens disposed within said rigid shell and extending substantially transverse to the longitudinal axis of said elongated housing and the rigid shell therein and connected to said rigid shell for passage of supply air therethrough to the firebox but arresting a flame from the firebox from passing back through said other end of the elongated housing, a hood attached to said elongated housing at the other end thereof, said hood being spaced from said other end of the elongated housing thereby providing air passageways about said other end of the elongated housing at opposite portions thereof which passageways are in communication with said other end of the elongated housing to permit the passage of supply air therethrough.

2. A flame arrester for attachment to the air intake of the firebox of a furnace comprising, in combination, a horizontally extending elongated casing having one end for attachment to the air intake of the furnace firebox, a plurality of fine-mesh screens disposed vertically across the interior of said casing and spaced each from the other, an end cover for the other end of said casing comprising a vertically extending semi-cylindrical enclosure for the lower portion of the other end of the elongated casing and an integral inclined roof closure attached to the upper end of the semi-cylindrical enclosure disposed over the remaining portion of said other end of the casing, said roof enclosure terminating in a lip spaced above and apart from said horizontal casing whereby a covered opening at said other end of the horizontal casing is provided to permit ingress of air therethrough and into the interior of said horizontal casing, said semi-cylindrical closure being open at its bottom end, and a baffle within said semi-cylindrical enclosure, said baffle being so shaped and proportioned as to provide a second air ingress passageway between its marginal edge and the interior of said semi-cylindrical enclosure.

3. A flame arrester for the air intake of a furnace firebox comprising, in combination, an elongated housing having one end thereof adapted to be connected with the air intake of a furnace firebox, a rigid shell disposed within said housing adjacent the other end thereof, means connecting said shell to said surrounding elongated housing providing a tight closure therebetween, a plurality of spaced apart fine-mesh screens disposed within said rigid shell and extending substantially transverse to the longitudinal axis of said elongated housing and the rigid shell therein and connected to said rigid shell for passage of supply air therethrough to the firebox but arresting a flame from the fire box from passing back through said other end of the elongated housing, a conical baffle having a plurality of spaced apertures in the walls thereof attached at its base to and in communication with the other end of said

elongated housing and a conical hood supportingly attached to said elongated housing and positioned over and in spaced relation to said conical baffle with the base end thereof positioned in spaced relationship adjacent the other end of 5 said elongated housing whereby a supply air passageway is provided leading from the space between the base end of the wall of said hood and the adjacent spaced other end of said elongated housing to the space between said conical 10 hood and said conical apertured baffle spaced within said hood.
